UNITED STATES PATENT OFFICE.

FREDERICK C. BLANCHARD AND PHILIP G. DARLING, OF BRIDGEPORT, CONNECTICUT,
ASSIGNORS TO THE CONSOLIDATED SAFETY VALVE COMPANY, OF BRIDGEPORT,
CONNECTICUT, A CORPORATION OF CONNECTICUT.

VALVE.

No. 889,895.

Specification of Letters Patent.

Patented June 9, 1908.

Application filed November 9, 1907. Serial No. 401,469.

To all whom it may concern:

Be it known that we, FREDERICK C. BLANCHARD and PHILIP G. DARLING, citizens of the United States, and residents of 5 Bridgeport, in the county of Fairfield and State of Connecticut, have invented new and useful Improvements in Valves, of which the following is a specification.

Our invention relates to safety valves such 10 as are used on steam boilers and its object is to eliminate back pressure on the valve.

As is well known, a safety valve must be set so as to be sensitive to even slight changes in the pressure of the steam and consequently, if, on the opening of the valve, any back pressure is added to the pressure of the spring by which the valve is set, the accurate working of the valve is seriously interfered with. The older types of safety valves 20 are commonly constructed with a cylindrical flange or sleeve which fits inside the skirt of the spring casing and is in sliding contact therewith, the latter having also a circumferential shoulder or ledge projecting into 25 the steam passage through which the steam exhausts from the valve. In this construction the steam not only exerts back pressure upon the annular ledge of the valve but too readily leaks into the spring casing through 30 the joint formed by the sliding flange and the skirt of the spring casing and there exerts back pressure on the main body of the valve itself. If, when the valve has 35 "popped," back pressure is developed on the valve, it will chatter opening and closing a number of times in rapid succession, thus interfering with its efficiency and injuriously wearing the parts. Back pressure on the valve also tends to hold the valve down and 40 reduce the opening of the valve and consequently its relieving capacity.

In the drawing A represents a safety valve casing, provided with a valve seat in which the valve B is seated; C is a spring casing 45 having an annular skirt C' projecting toward the valve; and containing a spring D which holds the valve B on its seat in the usual manner; F is the outer depending portion of the spring casing mounted on said valve casing; G is the muffler hood which may, if desired, be mounted on the flange of the spring casing; H is a steam passage; I is an inlet through which steam passes from the valve casing or to the muffler, and J is the adjusting ring. The feather head consisting of the

cylindrical flange E which is comparatively thin projects into the steam passage H and is in sliding connection with and fits outside of the annular skirt C' of the spring casing C and extends along said annular skirt for 60 a considerable distance. C' is sometimes grooved and a packing or piston ring inserted to keep this joint reasonably tight without undue sliding friction. The adjusting ring J is provided with an annular 65 rim extending upward into the steam passage H and in effect forming with the cylindrical flange E an annular flaring nozzle into and through which the steam passes from the huddling chamber. Preferably, the side 70 of this nozzle is conical in form as shown in the drawing, but it may be made in other forms without departing from our invention provided the shape of the orifice enables it to perform the well known functions of the expanding delivery nozzle of the "Venturi" tube. As a result of this construction the area of the feather head E at the top on which steam can exert back pressure is so 75 small that no appreciable pressure is exerted upon it. The steam in its rush upward from the flaring orifice formed by the upwardly extending rim of the adjusting ring and the upwardly extending flange E, clears 80 itself with a minimum of eddy-making and 85 flows freely along the wall of the said cylindrical flange E, and the rush of steam upward past the comparatively thin feather head is sufficient to prevent any steam from being forced down between the feather head 90 and the skirt of the spring casing into the spring casing itself and there exerting back pressure on the valve.

The behavior of safety valves, constructed as above described, indicates that the condition in the steam escape passage around and near the feather head is similar to that in steam injector tubes at points where the velocity and changing cross section of the steam jet are such that no lateral pressure is exerted on the sides of the tube, or such that free apertures in the tube perform the function of intake passages, showing that the internal condition at that point is tending toward a vacuum. In the safety valve, above 105 described, observation fails to detect any tendency of steam to escape through the joint between the feather head and skirt into the spring chamber and we are inclined to believe that the pressure conditions at the junc- 110

ture of the feather head with the skirt tend rather to draw air from the spring chamber than to force steam into it. The joint between the feather head and the annular skirt of the spring casing is practically steam tight, although sufficiently free to allow the feather head to slide readily.

Another advantage of our invention is that in the older types of safety valves there is 10 more back pressure when a muffler is used than there is without a muffler and therefore the valve must be adjusted differently or a differently cut adjusting ring must be used according as the valve is used with or without a muffler. In our invention, on the contrary, the bad effects of back pressure being eliminated, there need be but one adjustment of the valve regardless of its use with or without a muffler; this advantage results in 20 saving of time and trouble and in cost of manufacture.

What we claim and desire to secure by Letters Patent is:

1. In a safety valve, a valve casing provided with a valve seat, a valve coöperating with said valve seat, a spring casing having an annular skirt projecting toward said valve, said valve having a flange outside of and in sliding engagement with said annular skirt, 25 an adjusting ring surrounding and adjacent to the outer lip of the valve, and provided with a rim extending upwardly beyond the lower end of the flange of said valve, the flange and rim constituting a flaring nozzle to facilitate free flow of steam after it leaves the valve seat, and means to set said adjusting ring in any determined position.

2. In a safety valve, a valve casing provided with a valve seat, a valve coöperating 40 with said valve seat, a spring casing mounted on said valve seat, a muffler mounted on said spring casing, said spring casing having an annular skirt projecting toward said valve and said valve having a flange outside of and 45 in sliding engagement with said annular skirt, an adjusting ring surrounding and adjacent to the outer lip of the flange and provided with a rim extending beyond the lower end of the flange of said valve, the flange and 50 rim constituting a flaring nozzle to facilitate

free flow of steam after it leaves the valve seat, and means to set said adjusting ring in any determined position.

3. In a safety valve, a valve casing provided with a valve seat, a spring-operated valve coöperating with said valve seat, a spring casing, mounted on said valve casing, a muffler mounted on said spring casing said spring casing having an annular skirt projecting toward said valve and said valve having a flange outside of and in sliding engagement with said annular skirt, the outer surface of said flange being a cylindrical extension substantially equal in diameter to the extreme outer portion of said valve, an adjusting 60 ring surrounding and adjacent to the outer lip of the valve and provided with a rim extending upwardly beyond the lower end of the flange of said valve, the flange and rim constituting a flaring nozzle to facilitate free 65 flow of steam after it leaves the valve seat, and means to set said adjusting ring in any determined position.

4. In a safety valve, a valve casing provided with a valve seat, a valve coöperating 75 with said valve seat, a spring casing mounted on said valve casing and having an annular skirt projecting toward said valve, a muffler mounted on said spring casing, steam passages between the outer depending wall 80 and the annular skirt of said spring casing, passages from said steam passage to said muffler, said valve having a flange projecting into said steam passage and outside of and in sliding engagement with said annular 85 skirt, an adjusting ring surrounding and adjacent to the outer lip of the valve and provided with a rim extending upwardly beyond the lower end of the flange of said valve, the flange and rim constituting a flaring nozzle 90 to facilitate free flow of steam after it leaves the valve seat, and means to set said adjusting ring in any determined position.

Signed by us at Bridgeport, Conn., this sixth day of November 1907.

FREDERICK C. BLANCHARD.
PHILIP G. DARLING.
